UNITED STATES PATENT OFFICE.

HERMANN HEIM, OF OBER-DÖBLING, NEAR VIENNA, AUSTRIA-HUNGARY.

STOVE.

SPECIFICATION forming part of Letters Patent No. 393,231, dated November 20, 1888.

Application filed June 11, 1886. Serial No. 204,865. (No model.) Patented in Germany May 8, 1886, No. 38,987; in France May 8, 1886, No. 176,011; in Belgium May 8, 1886, No. 73,041; in England May 11, 1886, No. 6,376; in Italy March 31, 1887, XXI, 21,287, and XLII, 115, and in Austria-Hungary April 4, 1887, No. 41,442 and No. 6,689.

To all whom it may concern:

Be it known that I, HERMANN HEIM, manufacturer, a subject of the Emperor of Austria-Hungary, residing at Ober-Döbling, near Vienna, in the Province of Lower Austria, in the Empire of Austria-Hungary, have invented certain new and useful Improvements in Stoves, (for which I have obtained Letters Patent in the following countries: In Austria-Hungary by Letters Patent, Vienna, No. 41,442, and Budapest, No. 6,689, dated April 4, 1887; in Germany by Letters Patent No. 38,987, dated May 8, 1886; in France by Letters Patent No. 176,011, dated May 8, 1886; in Belgium by Letters Patent No. 73,041, dated May 8, 1886; in England by Letters Patent No. 6,376, dated May 11, 1886, and in Italy by Letters Patent, Vol. XXI, No. 21,287, and Vol. XLII, No. 115, dated March 31, 1887;) and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Referring to the drawings, Figures 1 and 2 show in vertical central sections, at right angles to each other, a stove constructed according to my invention. Figs. 3 and 4 are like views of the lower part of the fire-pot, showing a modification in the construction thereof. Fig. 5 is a horizontal section taken on line 1 1 of Fig. 3. Fig. 6 shows by a plan view a ring 35 to be arranged in the fire-pot above the grate to protect the wall of the fire-pot against the action of the fire. Figs. 7 and 8 are horizontal sections taken on line 2 2 and 3 3, respectively, of Fig. 1. Fig. 9 is a plan view of a 40 plate designed for introduction between the grate and fuel when said grate is to be removed. Fig. 10 is a view of the tool for removing the cover from the feed-hopper. Fig. 11 is an elevation of a portion of the intermediate casing, M'; and Figs. 12 and 13 are detail views showing by a vertical section and under side view, respectively, the draft-regulating devices.

The invention relates to that class of stoves in which the fuel is charged into the fire-pot and onto the grate from the top or from near the top of the stove; and it has for its object certain improvements whereby access may readily be had to any portion of the stove, and whereby better results are obtained and such stoves rendered more efficient in operation.

The invention consists in structural features and combinations of parts, substantially as hereinafter described, and particularly pointed out in the claims.

In the drawings, P indicates the fire-pot, which is composed of a head-section, P', a grate-section, P'', and one or more intermediate sections, P''. The said sections are preferably cylindrical in cross-section, but may be of any other form in cross-section and adapted to be fitted one on top of the other. The head-section P' has a short flue, p', to which the stove-pipe is attached, and it has also an inwardly-projecting charging-hopper, p, the mouth of which that opens into the fire-pot has its inner periphery made tapering inwardly or conical to form a conical seat for a cover or lid, L, that has a socket, l, by means of which and the poker (shown in Fig. 10) or other like instrument said lid may be readily removed or replaced. The general form of the charging-hopper p is conical, though it may be of any other form—as, cylindrical, prismatic, spheroidal, or pyramidal—and projects into the fire-pot at an angle to the vertical axis thereof.

The grate section or chamber and ash-pit P'' are of the form of a bent tube or segment of a hollow ring, semicircular or rectangular in cross-section, as shown in Figs. 1 and 2 and 3 and 4, respectively. It is provided with a tubular foot-piece, F, that is seated on an annular seat-plate, B', formed with the base B of the stove and connected thereto by radial arms b.

The object in making the foot of the fire-pot hollow is to provide an air-chamber through which air can freely circulate and prevent the bottom of the fire-pot from becoming unduly heated or from setting fire to the floor on which the stove may stand, the walls of

said air-chamber being provided with perforations b' for the free circulation of the air therethrough.

As shown in Figs. 1 and 2, the sections which 5 compose the fire-pot or stove proper are so constructed as to readily seat one on the other by overlapping joints, and the intermediate sections, P' , are preferably provided with radiating ribs c' , not only for increasing the radiating-surfaces of the stove, but also for the purpose of holding the inner casing in proper position, as hereinafter described.

To protect the section P' immediately above the grate-section P^2 from the action of the fire 15 on the grate, I prefer to interpose between it and the said grate-section P^2 a cast-iron ring, R , Figs. 1 and 2, which, in order to give it greater strength, I prefer to construct as shown in Fig. 3, having the seats r and r' formed by its 20 semi-cylindrical periphery, a portion of which is cut away to form the seat r' . One-half (more or less) of this ring is of greater vertical diameter or height than the remaining portion, the upper edge of the grate-section P^2 being shaped to receive this ring, so as to form a sort of interlocking joint at r^2 to prevent the sections from rotating on each other.

G is the grate, of any desired or usual construction, supported on a flange, g , or on lugs 30 formed on or projecting from the inner wall of the grate-section, so as to adapt the said grate for ready removal; and, if desired, a vertical grate, G' , Figs. 3 and 4, may be arranged on the front side and within the section P' above 35 grate G for the introduction of a poker for stirring up the fire.

When it becomes necessary to remove the grate G while there is fire in the stove, I provide a grate, G' , that consists of a perforated 40 plate, Fig. 12, adapted to be introduced into the fire-pot above the grates G and G' , as shown in Figs. 3 and 4, to prevent the fuel from falling down into the ash-box A .

For the purpose of regulating the draft, I 45 employ a door, D , that is hung from a horizontal pivot or hinge-pintle, D' , on which said door is not only free to swing, but also free to slide longitudinally, and when swung wide open will lie against lugs $l' l'$, formed on and 50 projecting vertically from the bearings L' of the door-hinge pintle D' . The door D is of such dimensions as to entirely cover the mouth or open front of the grate-section P^2 when in proper position, and it will be readily understood that by sliding said door more or less to one or the other side along its hinge-pintle 55 the said mouth or open front will be more or less uncovered and the draft thereby regulated.

In order that the draft when once adjusted 60 may not be interfered with by unauthorized persons, I provide a lock for said door, which consists of a spring-bolt, D^2 , one end of which engages a rack-bar, ℓ' , on the underside of the grate-section P^2 , and whose other end is screw-threaded for the reception of a key, d , by 65 means of which the bolt D^2 may be withdrawn

from the rack-bar ℓ' , as more plainly shown in the detached views, Figs. 13 and 14. The bolt is arranged within a tubular case, d' , projecting from the edge of the door or draft-slide D . 70

The several sections of the fire-pot are secured together and to the base B by means of tie-rods $E E$, one end of which is hooked and engages the radial arms b of the base B , the other ends of said rods being screw-threaded 75 for the reception of nuts $e e$, said screw-threaded ends passing through perforations in radial arms p , cast with the head-section P' , as more plainly shown in Fig. 2.

C is the outer sheet-metal cylindrical casing 80 supported from the base B and carrying the lid or stove-top section C' , covered by a lid, c' , provided, as usual, with openings for the escape of the heat. The said casing has at its lower end an opening that is constructed to 85 fit over the grate-section P^2 , so that the casing may be readily removed by simply lifting the same off the base. At its upper end the said casing C has an opening, e , in which is secured a conical door-frame, C^2 , provided with a door, 90 c^2 , the lower edge, c^3 , of which cone-frame projects over the outwardly-flaring wall of the feed-hopper, so that when fuel is introduced into said hopper it cannot fall between the fire-pot and the inclosing-case. The casing C is 95 also provided with an opening, c^4 , opposite the short flue p' of the fire-pot P , for the passage of the draft-pipe and its connection with said short flue.

H is the inner casing, which is shorter than 100 the casing C and surrounds the greater part of the fire-pot and serves to protect the outer casing from the action of the heat, and in order to adapt the same for removal I employ flexible sheet metal that is secured at its edges 105 by means of buttons h , engaging button-holes h' , Fig. 11, formed along said edges, so that said casing H may be readily unfastened, opened, and removed from around the fire-pot. Instead of buttons and button-holes, slots and 110 hooks or other like fastening devices may be employed, as will be readily understood.

Having now particularly described and ascertained the nature of my said invention and how the same is to be performed, what I claim, 115 and desire to secure by Letters Patent, is—

1. In a heater, a fire-pot having a portion of its shell deflected inwardly to form an inwardly-projecting opened feed-hopper, said feed-hopper being provided at its inner end 120 with a seat for a lid, substantially as and for the purposes specified.

2. In a heater, a fire-pot having a portion of its shell deflected inwardly at an angle to the vertical axis of said fire-pot to form an inwardly-projecting feed-hopper, said deflected portion of the shell being provided at its inner open end with a seat for a lid and at its lower outer edge with an outwardly-projecting flaring lip or flange, substantially as and for the 125 purposes specified.

3. In a heater, a fire-pot having a portion of

- its shell deflected inwardly at an angle to the vertical axis of said fire-pot, said deflected portion of the shell being gradually contracted to form an inwardly-projecting and inwardly-tapering feed-hopper, and provided at its inner open end with a seat for a lid, substantially as and for the purposes specified.
4. In a heater, a fire-pot having a portion of its shell deflected inwardly to form an inwardly-projecting feed-hopper and an outwardly-projecting flaring lip or flange, in combination with an inclosing-casing of greater diameter than the fire-pot, said casing being provided with an opening opposite the inwardly-deflected portion of said shell, said opening being provided with an inwardly-projecting lip or flange arranged to overlap the outwardly-projecting flange on said shell, substantially as and for the purposes specified.
5. In a heater, a fire-pot provided at its upper end with a horizontal short flue, p' , and having a portion of its shell deflected inwardly immediately below said short flue to form an inwardly-projecting feed-hopper, and a contracted vertical passage leading from the fire-pot to said flue, said deflected portion of the shell being provided at its inner open end with a seat for a lid, substantially as and for the purposes specified.
6. In a heater, the combination, with the fire-pot and grate and a feed-hopper formed by a recess or depression in said fire-pot, of an outer inclosing-casing provided with a fuel-door opposite the feed-hopper, an intermediate casing shorter than the outer casing arranged to form a heat-chamber between it and the fire-pot and the outer casing respectively, and a bridge extending from the feed-hopper to the fuel-door to prevent fuel falling into the heat-chambers, as described.
7. The grate-section P^2 , substantially of the form as shown and described, in combination with the hollow foot-piece F , provided with air-ports, substantially as and for the purposes specified.
8. The combination, with the ash-pit section of the grate-chamber provided underneath its open end with a toothed rack, and a sliding door for said open end, of a lock for said door, comprising a spring-bolt arranged within a housing and adapted to engage the teeth of the rack, and a tubular key screw-threaded interiorly to screw onto the bolt end, substantially as and for the purposes specified.
9. In a heater, a fire-pot having a feed-hopper at an angle to the vertical axis of said fire-pot, said hopper being formed by an inwardly-projecting tubular portion, the lower edge of the mouth or feed end of said portion flaring outwardly, in combination with an inclosing-casing having a fuel-aperture registering with the feed-hopper, and a door for said aperture provided with an inwardly-projecting flange overlapping the outwardly-flaring edge of the hopper, substantially as and for the purposes specified.
10. In a stove, a grate-chamber or ash-pit, P^2 , having the form of a bent tube or segment of a hollow ring provided with a seat for a grate, the horizontal grate G , removable from said seat, and the vertical grate G' , arranged in front of grate G and removable from the chamber, substantially as and for the purposes specified.
11. In a heater, a fire-pot, a feed-hopper formed by a depression or recess in said fire-pot, whereby its inner area is contracted, and a horizontal short flue, p' , formed above said contracted portion, in combination with an inclosing-casing provided with a fuel-aperture opposite the feed-hopper and an aperture opposite the flue p' for the passage of the smoke-pipe, and a base for supporting said parts, with which base the inclosing-casing is detachably connected, whereby said casing may be removed after disconnecting the smoke-pipe without disturbing the fire-pot, substantially as and for the purposes specified.
12. In a stove, a fire-pot composed of a head-section provided with projecting arms, a grate-section or ash-pit having the form of a bent tube or segment of a hollow ring, semi-circular or angular in cross-section, a hollow foot-piece depending from the curved bottom of said section, and one or more intermediate sections, in combination with a base, B , provided with radial arms, a seat-plate, B' , for said foot-piece seated axially on the radial arms of the base B , and tie-rods for connecting the arms of the head-section of the fire-pot with those of the base, substantially as and for the purposes specified.
13. The combination, with the fire-pot P , constructed substantially as described, and the base B , to which said fire-pot is detachably connected by the rods E , of the outer casing, C , loosely seated on base B and provided with a fuel-aperture and an aperture for the passage of the smoke-pipe, and an intermediate shorter open-ended casing, H , also loosely seated on base B and having its vertical meeting edges detachably connected together, substantially as and for the purposes specified.

In testimony whereof I affix my signature in presence of two witnesses.

HERMANN HEIM.
